(57) **CLAIM**

The ornamental design for a soaring bird kite, as shown and described herein.

DESCRIPTION

FIG. 1. Is a perspective view of my soaring bird kite design; FIG. 2. Is a left side view thereof, the right side view being identical thereto;

FIG. 3. Is a bottom view thereof;

FIG. 4. Is a top plan view thereof;

FIG. 5. Is a front elevational view thereof; and,

FIG. 6. Is a rear elevational view thereof.

The structure shown in broken lines are for illustrative purposes only and form no part of the claimed design.
